UNITED STATES PATENT OFFICE.

CHARLES B. TEWKSBURY, OF BOSTON, MASSACHUSETTS, ASSIGNOR, BY MESNE ASSIGNMENTS, TO SAFEGUARD TAG COMPANY, OF PORTLAND, MAINE, A CORPORATION OF MAINE.

TAG.

1,239,844.

Specification of Letters Patent.

Patented Sept. 11, 1917.

Application filed June 25, 1912. Serial No. 705,757.

To all whom it may concern:

Be it known that I, CHARLES B. TEWKSBURY, a citizen of the United States, and resident of Boston, in the county of Suffolk, 5 in the State of Massachusetts, have invented new and useful Improvements in Tags.

My invention relates to that class of tags in which the body of the tag is provided with reinforcing material to prevent tearing.

10 My object has been to provide a tag having reinforcing material so attached to the material forming the body of the tag, that it is practically impossible to separate the reinforcing material from the body of the tag. The strength and durability of the tag is thus limited, not alone to the tensile strength of the material of the body of the tag, but to the combined strength of the reinforcing material and the body of the tag.

20 Another object is to provide a tag having the thickness of the reinforcing material apparent on one surface of the tag only, where the tag has a multi-ply body, leaving the other surface flat or smooth to facilitate its 25 inscription.

Another object is to provide an arrangement of the reinforcing material so as to protect the longitudinal edges of the tag, and thus add strength and durability.

30 For the purpose of illustrating my invention, I have shown and described a tag having a multi-ply body portion with a flat metal reinforcing strip through its approximate longitudinal center and rounded reinforcing material along the sides, but I do not limit myself to the precise shape, location or kind of reinforcing material herein shown and described, nor to the method of attaching the same to the tag material, nor 40 to a tag having a multi-ply body portion.

It is apparent that it is not necessary to have the reinforcing material of flat metallic strips, but a wire with roughened or serrated surface would answer the purpose 45 as well in some cases; in that event the reinforcing material, such as wire, could extend beyond the body of the tag for attaching purposes and the roughened or serrated surface would provide an efficient bond 50 when the plies of material are cemented together under heavy pressure, that would be difficult if not impossible to obtain in any other way.

I accomplish these objects in the manner 55 hereinafter specified.

Figure 1 is a view of the upper face of a tag having reinforcing material shown in dotted lines except where part of the face or upper layer of the material forming the body of the tag is broken away.

60

Fig. 2 is a cross-sectional view along line A A in Fig. 1.

Fig. 3 is an enlarged sectional view of a modified form of construction.

Fig. 4 is an enlarged view of Fig. 2.

65

Fig. 5 is an enlarged detail view of the central reinforcing strip.

The form of construction shown in Figs. 1, 2 and 4 is that of a tag the body of which is formed by folding a single sheet of tag 70 material back upon itself until the edges of the two sides meet as shown by dotted line 1.

The modified form of construction shown in Fig. 3 is that of a tag formed of two distinct layers or plies of tag material with the 75 side reinforcing material set in toward the longitudinal center of the tag.

2 is the smooth face or flat upper layer of tag material which is adapted for such inscription as it may be desired to place upon 80 the tag.

3 is the under face or layer of tag material which may be formed as hereinbefore stated by folding the tag material back upon itself. The two layers of material thus formed may 85 be cemented together by any well known adhesive.

4 is a strip of reinforcing material, preferably metallic between the layers of tag material.

90

5, 5 are strands of reinforcing material also between the layers of tag material. These latter may be of metal such as wire, or may be composed of string or tape or may be entirely eliminated.

95

As shown in my preferred form of construction, Figs. 1, 2 and 4, these strands 5, 5 are placed substantially along the longitudinal edges of the tag where the tag material is creased to fold it back upon itself.

100

When the layers of tag material are pressed together after the insertion of the reinforcing material and the adhesive, the several parts are pressed together in such manner as to force the reinforcing material toward one face of the tag only and, with the layer of tag material on that side, to form the flanges as shown in Figs. 2 and 4.

105

I preferably furnish strip 4 with serrated or roughened surfaces as shown in Figs. 1 110

and 5. These roughened surfaces furnish an excellent hold for the adhesive and when the layers of tag material are subjected to pressure the paper or other material forming the body of the tag is pressed into the serrations of strip 4 and thus secures a strong union, so that it is difficult to detach either layer of the tag material from the reinforcing material 4.

10 The insertion of strands 5, 5 furnishes additional strength and prevents the tearing of the tag laterally. These strands are illustrated as being without serrations, but I do not limit myself to the precise form of construction, shape or condition shown.

In order to secure a still more perfect union of strip 4 with the body of the tag and to furnish an eyelet for the purpose of attaching the tag by wire, string or otherwise 20 to a package, I provide one or more apertures 7, 7.

In the drawings I have shown two such apertures substantially circular in form, but I do not limit myself to any precise number 25 or shape or location. An important feature of the invention resides in the means by which the apertures are provided with round edges to prevent cutting the string and at the same time providing means for additionally securing the tag material and the reinforcing strip together. This is accomplished by forming an eyelet from the reinforcing material the edges of which engage the tag material.

35 These eyelets may be formed by punching the two layers of the tag material and the strengthening material 4, then by any well-known means forcing the material 4 and such portion of the tag material as may be 40 carried with it toward the surface of the tag and then turning the edges of the punched portion of the strip 4 back upon itself until it clenches itself and that surface of the tag together. There is advantage in this form of construction as I am 45 able thus to secure not only additional security in fastening the material 4 to the tag material but also from the fact that the aperture is provided with a round smooth edge for the string or other means used to fasten the tag to an article.

It will be observed that one or more of the eyelets in the preferred form of the invention as illustrated in Figs. 1, 2, and 4, engage a portion of each of the abutting edges of the tag material indicated by the dotted line 1. This construction provides means for preventing either of the edges which might become loosened, from springing away from 55 the reinforcing material.

What I claim and desire to secure by Letters Patent is,—

1. A tag formed from a sheet of material

having its longitudinal edges folded back so as to abut and a reinforcing strip underlying 65 the abutting edges, said material and reinforcing strip being punctured and bent over so as to form an eyelet and to clench the reinforcing strip to each of the longitudinal edges of said other material.

2. In a tag having a multi-ply body portion, the outside surface of one ply being smooth, the combination of a metal reinforcing strip with a serrated surface between said plies, said body portion and said reinforcing strip being punctured and bent over 70 upon themselves so as to form an eyelet and to clench the metal strip to a ply of the body portion and to form a smooth, rounded edge entirely around said puncture, 75 and a strand of flexible reinforcing material between said plies running substantially parallel to the metal reinforcing strip but nearer the longitudinal edge of said tag.

3. In a tag having a multi-ply body portion, the combination of a metal reinforcing strip between said plies, said body portion and said reinforcing strip being punctured and bent back upon themselves so as to form 80 an eyelet and to clench the metal strip to a 85 ply of the body portion and to form a smooth, rounded edge entirely around said puncture, and a strand of flexible reinforcing material between said plies running substantially parallel to the metal reinforcing 90 strip but nearer the longitudinal edge of said tag.

4. A tag which comprises in combination a body formed of two layers of sheet material adhesively united together, a longitudinal reinforcement for said body, consisting of a flat relatively wide metal strip disposed between said layers and adhesively held in place therebetween, said strip and layers having coinciding holes therein for 105 the reception of means for attaching said tag to a parcel, and combined attachment protecting and sheet material retaining means, integrally united to and formed directly from the metal of said strip, at said hole 110 therein, for preventing said strip from abrading said attaching means at any point whatsoever in the peripheral wall of said hole and for holding the edge of the hole in one layer of said sheet material close to said 115 metal strip, securely around said periphery of said hole.

In witness whereof I have hereunto set my hand in the presence of two subscribing witnesses, this the twenty second day of 120 June, 1912.

CHARLES B. TEWKSBURY.
